UNITED STATES PATENT OFFICE

CHARLES LEO DALY, OF BROCKTON, MASSACHUSETTS, ASSIGNOR, BY MESNE ASSIGNMENTS, TO ARDEN BOX TOE COMPANY, OF WATERTOWN, MASSACHUSETTS, A CORPORATION OF MASSACHUSETTS

SOFT BOX TOE

Application filed January 18, 1927. Serial No. 161,775.

The usual soft box toe is an all-leather, all-cork, or all-rubber blank or a combination of any of these with a slight percentage of thermoplastic impregnant to give the blank some 5 stiffness. In assembling this type of blank in the toe of the shoe the usual practice is to lay the blank between the lining and the upper material without stitching it at the tip line. The tendency of the foot to work 10 within the shoe when the shoe is worn, however, causes the leather tip to slide or creep on the blank, producing a wrinkle at the toe and spoiling the appearance of the shoe. Also 15 the lining between the soft box toe blank and the foot will drop away from the blank. Where it is attempted to stitch the soft box toe to the toe tip, the blank will wrinkle below the stitch line.

To the end, therefore, of providing a soft 20 box toe blank which may be firmly anchored to the toe tip of the shoe without stitching, and which when so incorporated will retain its position relative to the tip without wrinkling, and hold the toe lining up from the 25 toes, I have devised my present invention. According to it, I apply to either or both faces 30 of the soft toe blank, either adjacent the tip line only or through a substantial portion of the blank, a coating of latently adhesive material which is capable of being rendered adhesive upon treatment, as by heat treatment, by wetting, immersion in a solvent, or by exposure to the solvent vapor, and which coating is different in character and results from 35 the thermoplastic impregnant which is sometimes used to stiffen the body of the soft toe blank.

Before the blank is lasted, this coating is 40 rendered adhesive so that it will anchor the blank to the toe tip vamp and, if desired, to the lining of the shoe, whereby to of itself adhesively fix the blank within the shoe, thus avoiding the necessity for stitching in the blank or for simply laying it loosely in the 45 toe as in present methods. Moreover, the adherent coating reinforces the blank along its line of greatest weakness thus not only preventing wrinkling but imparting to the soft toe a slight degree of stiffness which enables 50 the shoe better to hold its shape.

In the accompanying drawings I have illustrated embodiments of my invention which I have found satisfactory in practical use.

Fig. 1 is a partial section through a lasted upper showing a soft box toe blank assembled therein in accordance with my invention. 55

Fig. 2 is a face view of the blank removed.

Fig. 3 is a vertical section on the line 3—3, of Fig. 2, and

Figs. 4, 5 and 6 are vertical sections showing modifications. 60

I have indicated at 1 a soft box toe blank. This blank may be of any usual material, and if desired, may be lightly impregnated with a thermoplastic penetrant, usually of 65 bituminous origin, and which penetrant acts as a stiffener for the blank.

According to my invention I coat one or both faces of the blank, preferably the outer face and preferably adjacent the tip line 70 edge of the blank, with a suitable adhesive coating 2. The coating 2 may be a relatively narrow band of adhesive adjacent the tip line edge, as shown in Figs. 2 and 3, or it may extend over the entire outer face of the 75 blank, as shown in Fig. 4, or over the entire inner face, as shown in Fig. 5, or over both faces as shown in Fig. 6.

This coating is normally hard and dry, but may be softened in any manner to render it adhesive, as by heat treatment, by wetting, by dipping in a solvent or by exposure to the solvent vapor. When sufficiently softened or otherwise rendered adhesive, the coating adherently connects the blank to the toe tip 3, lining and doubler 4 and vamp 5 of the shoe, thus avoiding the necessity for stitching said parts through and through the blank. The coating may be 80 of any desired material which is substantially different in character and result from the thermoplastic impregnant with which the blank is sometimes stiffened. It may be hard glue, dextrine, gutta-percha, rubber or any bituminous or resinous material which is capable of being rendered sticky on treatment. 85

When the coating is rendered adhesive and the blank lasted in the shoe, the coating positively fixes the blank against move- 100

ment relative to the toe tip. The lining cannot, therefore, pull out with the last when the last is withdrawn from the formed toe, as frequently happens with a loosely laid blank, and the blank itself will not slide or creep on the tip and thus wrinkle under the flexations of the shoe in walking. Moreover, the stitches 6 which fasten the overlapping vamp and toe tip to each other do not have to be carried through the blank. The coating acts as a stiffener, particularly at the tip line edge where the blank is weakest, and hence results in a blank of increased stiffness.

15 What I therefore claim and desire to secure by Letters Patent is:

1. As a new article of manufacture, a soft flexible one piece box toe blank carrying an external coating of latently adhesive material capable when rendered adhesive of forming the sole connecting medium between the blank and the tip and vamp of a shoe and when hardened acting to stiffen the blank adjacent to its tip line edge.

25 2. As a new article of manufacture, a soft flexible one piece box toe blank carrying on both faces an external coating of latently adhesive material capable when rendered adhesive of forming the sole connecting medium between the blank and the tip and vamp of a shoe and between the blank and the shoe lining and when hardened acting to stiffen the blank.

3. As a new article of manufacture, a soft flexible one piece box toe blank containing a thermoplastic stiffening agent, and carrying a coating of water softenable stiffening and adhesive agent capable when rendered adhesive of forming the sole bonding medium of said blank with adjacent parts of the shoe in which it is assembled and when hardened acting to stiffen the toe portion of the shoe.

In testimony whereof I affix my signature.
CHARLES LEO DALY.
